UNITED STATES PATENT OFFICE.

WILLIAM MORGAN, OF FORT PLAIN, NEW YORK.

DESIGN FOR A TOY-FAN BLADE.

SPECIFICATION forming part of Design No. 32,087, dated January 9, 1900.

Application filed November 29, 1899. Serial No. 738,738. Term of patent 7 years.

To all whom it may concern:

Be it known that I, WILLIAM MORGAN, a subject of the Queen of Great Britain, residing at Fort Plain, in the county of Montgomery and State of New York, have invented and produced a new and original Design for Toy-Fan Blades, of which the following is a specification.

In the accompanying drawings, forming part of this specification, in which like reference characters denote like parts in the several views, Figure 1 is a plan view of a toy-fan blade embodying my new design, and Fig. 2 an edge view thereof.

Referring more particularly to the drawings, the leading or material feature of my design consists of two blades or lobes A A, which are approximately circular in form and are arranged laterally and connected by a central web B of unvarying width, the length of said web as measured between the lines of its connection with the lobes or blades A A being approximately equal to the radius of each of said circular lobes or blades, and the edges of said web at the portions thereof where they are merged into the edges or peripheries of

said blades or lobes are curved. The central web B is provided with three circular perforations C, arranged in a series in the longitudinal center thereof and of approximately equal 30 diameter. The blades or lobes A A and web B are twisted longitudinally, whereby the periphery of each of said lobes or blades is deflected or curved upon opposite sides, and the web A is so twisted that when viewed edge- 35 wise its edge portions appear to cross centrally, as shown in Fig. 2, the entirety presenting when viewed edgewise, as in Fig. 2, the appearance of an elongated figure 8.

Having fully described my invention, what 40 I claim as new, and desire to secure by Letters Patent, is—

The design for a toy-fan blade, herein shown and described.

In testimony that I claim the foregoing as 45 my invention I have signed my name, in presence of the subscribing witnesses, this 28th day of November, 1899.

WILLIAM MORGAN.
